UNITED STATES PATENT OFFICE.

LUZERNE W. HOUSE, OF WATERLOO, NEW YORK.

LAP-ROBE.

1,282,581.

Specification of Letters Patent. Patented Oct. 22, 1918.

Application filed March 16, 1918. Serial No. 222,951.

To all whom it may concern:

Be it known that I, LUZERNE W. HOUSE, a citizen of the United States, residing at Waterloo, in the county of Seneca and State of New York, have invented certain new and useful Improvements in Lap-Robes; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in lap robes and consists essentially in the provision of means for supporting the robes by straps adjustably fastened to the upper edge of the robe designed to be passed about the neck of the person, while loops are secured to the inner surface of the robe through which the arms of a person may be placed to relieve the weight of the robe from the straps around the neck.

The invention consists of a simple and efficient device of the nature having various details of construction, combinations and arrangements of parts which will be herein-after fully described, shown in the accompanying drawings and then specifically defined in the appended claim.

My invention is illustrated in the accompanying drawings which, with the letters of reference marked thereon, form a part of this specification and in which:

Figure 1 is a perspective view of the application of my invention, and

Fig. 2 is a detail view showing the loops 40 on the inner surface of the robe.

Reference now being had to the details of the drawings by letter:

A designates a robe and B are tabs which are fastened at E to the outer surface of 45 the robe preferably near its upper edge, and to each of said tabs a buckle F is attached. Straps K are adjustably connected to the buckle and each is provided with a socket member L adapted to engage a lug N fastened to the robe forming a glove buttoner 50 fastener and which will permit the strap to be easily and quickly adjusted in place.

There are preferably a plurality of straps similarly attached one for each occupant 55 sitting upon the same seat. Straps T vertically disposed are fastened at their ends at any suitable locations, preferably above the center of the robe and through which the hands and arms of the person protected by 60 the robe may be placed and which will serve to relieve the adjustable straps of the weight of the robe by the latter being held up by the arms of the person.

What I claim to be new is:

A lap robe, tabs fastened thereto, buckles secured to the tabs, straps adjustably connected to the buckles, and glove buttoner fasteners for attaching the straps to the robe, and straps fastened at their ends to 70 the inner face of the robe through which the hands and arms of persons may be passed.

In testimony whereof I hereunto affix my signature in presence of two witnesses.

LUZERNE W. HOUSE.

Witnesses:

WILLIAM F. BACON,
